CLAIM

The ornamental design for a cluster display screen or portion thereof with a graphical user interface, as shown and described.

DESCRIPTION

FIG. 1 is a front view of a cluster display screen or portion thereof with a graphical user interface showing our new design; and,

FIG. 2 is an enlarged view of FIG. 1.

The broken lines illustrate a cluster display screen or portion thereof that form no part of the claimed design.

1 Claim, 1 Drawing Sheet
